[57] ABSTRACT

The carburetor produces increased fuel-air ratio towards the reduced airflow end of the family of constant-throttle variable-R.P.M. curves (FIG. 7 curves *i j k*). This is obtained by augmentation of the Venturi suction by means of a Laminar Flow Matrix, which produces a nearly linear relationship between airflow and metering suction. In order to maintain the correct roadload curve despite this low-end increase of the metering signal, a bypass throttle, controlled by the main throttle, resets the fuel-air ratio to the correct value (FIG. 6). The schedule of bypass throttle opening relative to main throttle opening determines the roadload curve.

**CARBURETOR FOR AUTOMOTIVE ENGINES
WITH A METERING SUCTION PARTLY DERIVED
FROM A LAMINAR AIR FLOW MATRIX**

BACKGROUND OF THE INVENTION

The invention relates to automotive carburetors which are calibrated to a lean mixture, in order to reduce both harmful emission products and fuel consumption.

Since the fuel-air ratio of convention carburetors leans out at reduced airflow, the leanest possible calibration is limited by this tendency to further reduce the mixture strength at low loads.

Prior art carburetors have avoided this low-end leaning out by means of airvalves. These are devices which increase the metering suction by means of air throttling (choking) ahead of the fuel discharge. Typically, these airvalves are operated by suction sensitive devices, which tend to CLOSE these airvalves as the airflow is REDUCED. It is possible to produce flat fuel-air ratio curves with these known devices, or even curves which are getting richer towards the low airflow end.

Automotive engines equipped with such air valve carburetors, (or equivalent compensating devices) and calibrated to a very lean flat fuel-air ratio curve over the cruising range, preforms well for all throttle positions, but only in steady state operation, that is only for the constant vehicle speed obtained for each throttle position.

However, if the throttle-opening is increased suddenly, these carburetors suffer from lagging and hesitation during the acceleration which follows an increase in throttle-opening, when calibrated to a lean roadload curve. A temporarily enriched mixture would be required, in order to allow the engine to speed up to the new powerlevel and R.P.M. belonging to the larger throttle opening.

It would be easy enough to calibrate the airvalve operating mechanism in such a manner that it produces sufficiently strong mixture enriching at low airflows, in order to achieve good transient response. However, this OVER compensation is not practical, since it would also produce a rich fuel-air ratio at low-load steady-speed operation, as will be more fully explained later.

FIG. 1 shows a typical roadload curve for a CONVENTIONAL carburetor (without airvalve). The fuel-air ratio is plotted against the airflow, and each point of this curve is measured at the constant engine and vehicle speed obtained on a level road, for different throttle openings.

The curves *a*, *b* and *c*, represent constant-throttle variable-R.P.M. "Transient" curves. Curve *b*, for instance, occurs when the throttle opening is suddenly increased from, for instance, 10° at point I to the 35° position, and then held steadily in this 35° position. The vehicle will now accelerate from 20 m/h ALONG THE CURVE *b*, increasing the R.P.M. until the airflow of 50 CFM at the intersection of curve *b* with the roadload curve is reached at 60 m/h.

The fuel-air ratio shown by the transient curves *a* and *c* of a conventional carburetor tend to lean out at low R.P.M. and airflows. Consequently, when the throttle was suddenly opened from its 10° position at point I, to 35°, the fuel-air ratio dropped of to point II. This is the cause of the engine hesitation and sudden powerloss in "transient" driving conditions.

FIG. 2 shows the same constant-throttle, variable-R.P.M. curves *d* and *e*, if they are corrected by the prior art airvalves. With the aid of the air-valve, these curves are now sloped in the desired direction of enrichment towards low airflow, thus preventing hesitation in transients.

However, as FIG. 2 shows, the roadload curve itself will, through the effect of the same airvalve, also get richer for smaller throttle positions, thus ruining the objective of low fuel consumption and emission numbers at small loads in steady speed driving.

In other words: The enriching done at low airflows by means of the prior art airvalves is simply limited by fuel-air ratio calibration requirements at low airflows, as expressed in the desired roadload fuel-air ratio curve. If the transient curves are properly corrected, an undesirable OVER-correction of the roadload curve also results.

There exists two opposing requirements: For low airflow steady-speed operation, along the roadload curve, a LEAN fuel-air ratio is required. On the other hand, for "transients," during the acceleration along the constant-throttle variable-R.P.M. curves, a RICH mixture at the low end of these curves is required.

The desired and ideal shape of fuel-air ratio curves, which fulfills these OPPOSING requirements is shown in FIG. 3. Here, the transient curve *f,g,h* are getting richer towards small airflows, whereas the roadload curve stays flat, at a constant lean fuel-air ratio, over the entire cruising range. This chart illustrates the basic difficulty in fulfilling the just mentioned theoretically best fuel-air ratio prescription, namely, that the SAME airflow, of for instance 25 C.F.M., should produce a fuel-air ratio of 0.057 in the 15° throttle position on the roadload curve, (that is for steady vehicle speed), but should also produce a richer fuel-air ratio of 0.062 if this same 25 C.F.M. airflow is traversed with a throttle position of 35°, during an acceleration along curve *g*.

The invention gives novel means which, for the first time, achieve these two contradictory requirements. This is done by two mechanism or means acting IN COMBINATION: The first is the known airvalve or the, for this purpose newly used, Laminar Flow Matrix, which bends the constant throttle variable R.P.M. curves *f g h* into the desired backwards slope shown in FIG. 3. The second mechanism is a variable air-bypass system, which is coupled to the throttle and which "resets" the roadload-fuel air ratio curve to the desired lean values at low loads. (FIG. 6)

Thus, the invention makes it possible to calibrate the carburetor to an extremely lean roadload curve, and yet preserve good "transient response" (acceleration) during sudden change from any chosen throttle position to any other chosen throttle position. In tests with this new carburetor, this automatic changing of the fuel-air ratio from "transient rich" to "roadload lean" has proven to do away with the acceleration pump, and furthermore provides an entirely new freedom to calibrate the carburetor to the most favorable lean roadload curve, without being compromised by the formerly resulting poor transient response, which would occur in a conventional carburetor, calibrated to the same lean values.

SUMMARY OF THE INVENTION

This invention relates generally to carburetors for internal combustion engines and pertains more particularly to emission surpassing carburetors as used on automotive engines. These carburetors are operating with the relatively lean fuel-air ratios which give the lowest percentage of undesirable emission products. The carburetor according to the invention produces a set of new metering curves (FIG. 3) which permit to operate an internal combustion engine with lean mixture calibration (down to 0.053 fuel-air-ratio) along the roadload curve and yet avoids the hesitation and lagging occurring with conventional lean carbureted engines upon increasing the throttle openings, that is in transient operation (curves *f*, *g* and *h*). The invention consists of means to realize these new metering curves.

In the simplest embodiment of the invention, the new carburetor employs a laminar flow matrix arranged ahead of the Venturi (FIG. 6, primary stage carburetor on right side shows the invention).

The Venturi 3 produces a metering suction acting on the fuel discharge orifice 1, which rises (approximately) with the square of the airflow (see FIG. 4 curve 1). The Laminar Flow Matrix gives a linear relation between metering suction and airflow. (FIG. 4 curve II). If both a Venturi and a Laminar Flow Matrix are combined, a suction curve of intermediate curvature of the metering suction, plotted against airflow, is produced. (FIG. 4 curve III).

The fuel-air ratio curve generated by the metering suction curve according to FIG. 4 III, that is by means of a Laminar Flow Matrix and a Venturi combined, becomes richer at part throttle operation (FIG. 5, curve IIIr). As explained in the chapter "Background," this is desirable for the family of constant-throttle variable-R.P.M. curves, but undesirable for the roadload curve.

According to the invention (FIG. 6), the roadload curve of a carburetor with a Laminar Flow Matrix (6) and a Venturi 3 is "reset" into the required correct shape by means of a bypass throttle 8 which is driven by a cam 12 (or other scheduling means) attached to the throttle shaft 4. The opening sequence of this airvalve is scheduled to reduce the metering suction which acts on the fuel orifice 2 to the required amount, at each point of the roadload curve, as shown in the pictures of the throttle opening sequence of FIG. 7. Thus, the cam shape connecting the two throttles can be selected to produce the most desirable roadload curve.

The interconnection between the main throttle and the bypass throttle is purely mechanical (and NOT manifold suction operated, as in many known air valve carburetors). Consequently, the bypass throttle "resets" the fuel-air ratio strength only when the main throttle opening is changed; it corrects the roadload curve from the shape of FIG. 5 III to the desired shape of FIG. 7. For constant throttle position airflow changes however, (curves *i,j,k*, FIG. 7) the mechanical connection causes the bypass throttle to remain in a constant position. Thus, the family of constant-throttle variable-R.P.M. curves becomes enriched at the lower air-flow end, under the influence of the matrix.

The following example will illustrate how this affects transient throttle conditions (FIG. 7). When operating the car with 10° throttle opening at a steady 20 m/h, the

carburetor produces an 0.057 fuel-air ratio with an airflow of 15 C.F.M. When the throttle is now SUD-DENLY opened to the 35° position, the airflow grows to 25 C.F.M., according to the increased throttle opening, with still the same 20 m/h. The carburetor operation has now been shifted to point II of the low end of the 35° constant-throttle variable-R.P.M. curve *j*. The new 25 C.F.M. airflow intersects this curve at the fuel-air ratio 0.062. Consequently, with the sudden throttle movement from 10° to 35°, the fuel-air ratio snaps up from 0.057 to 0.062 (without the help of conventional "crutches," as acceleration pumps or powervalves).

The increased throttle opening now produces an acceleration of the vehicle, along the 35° constant throttle curve *j*, until the steady state condition at the airflow of 50 C.F.M. is reached at the intersection with the roadload curve. Here, the carburetor has returned to produce the economical 0.057 fuel-air ratio, so that in the following steady speed driving the engine again works with favorable low emission ratio.

From the foregoing explanation it is apparent that, despite the powerloss inherent in the calibration to a very lean cruising fuel-air ratio for steady speed driving, acceleration without hesitation still takes place when the throttle opening is increased, because every positive throttle opening change immediately shifts the carburetor metering up to a best power producing richer mixture at a low airflow point of the new setting to a higher constant throttle position curve. As the engine subsequently accelerates, it returns to the lean roadload curve.

The relative dimensioning and the distribution of the metering suction between the Laminar Flow Matrix (FIG. 6 Part 6) and the Venturi 3 determines the slope of the constant-throttle variable-R.P.M. curves. For instance, a short, small pressure drop producing Laminar Flow Matrix can be combined with a Venturi possessing a narrow throat. Some engines may even require completely flat metering curves. Then, the pressure drop of the Laminar Flow Matrix is reduced to a small fraction of the Venturi suction, and is used only to correct the tendency of pure Venturi metering to grow leaner at low airflows.

The selection of the mechanical scheduling between the main throttle and the bypass throttle, (that is the shape of the cam 12), determines the shape of the roadload curve.

In carburetors with conventional correction means, such as airvalves, a change in the slope of the constant throttle variable-R.P.M. curves is always resulting in an equivalent change of the slopes of the roadload curve. The new system permits for the first time to calibrate BOTH kinds of metering curves separately, to the best shape demanded by the engine. Present demands of a flat lean cruising power roadload curve can be combined with constant-throttle variable-R.P.M. curves, which exhibit a slope giving richer ratios at low R.P.M.

BRIEF DESCRIPTION OF DRAWINGS

FIG. 1 shows conventional metering curves.

FIG. 2 shows the metering curves of a conventional carburetor with an airvalve.

FIG. 3 shows the metering curves which are the aim of the invention.

FIG. 4 shows three basic metering suction creating devices and their suction curves (venturi, laminar flow matrix an a combination of both).

FIGS. 4-A, 4-B and 4-C respectively, in fragmentary diagrammatic form, illustrate the three types of carburetors employed in developing the curves of FIG. 4.

FIG. 5 shows the fuel-air ratio curves obtained with the devices of FIG. 4.

FIG. 6 shows one schematic section of one form of execution of the invention, containing the basic components of invention.

FIG. 7 shows the metering curves obtained with the carburetor of FIG. 6 and shows furthermore different throttle positions of the carburetor of FIG. 6, for different airflows.

FIGS. 7-A, 7-B, 7-C, 7-D, 7-E and 7-F respectively, in diagrammatic form, illustrate the carburetor structure of FIG. 6 in varying operating positions corresponding to indicated areas of operation depicted in FIG. 7.

FIGS. 8-A, 8-B and 8-C illustrate a modification of the carburetor of FIG. 6, in three different throttle positions.

FIGS. 9, 11, 12, 13 and 14 show schematically various devices designed to substitute the laminar flow matrix. (FIG. 10 gives comparative suction curves for a laminar flow matrix and its substitute.)

FIG. 14-A is a cross-sectional view taken generally on the plane of line A—A of FIG. 14 and looking in the direction of the arrows.

FIG. 15 fragmentarily illustrates a carburetor embodying the teachings of the invention with a reset device controlling the position of an air bypass throttle.

FIG. 16 somewhat in schematic form illustrates a carburetor constructed in accordance with the teachings of the invention wherein air bleed means is employed generally upstream of the induction passage throttle valve means.

FIG. 17-A illustrates in simplified form, a carburetor in which air bleed means, functionally equivalent to that of FIG. 16 is controlled by a plate-type valving member.

FIG. 17-B is a simplified view taken generally on the plane of line B—B of FIG. 17-A and looking in the direction of the arrows.

FIG. 18 is a graph of the fuel-air ratio curves obtained by the carburetor of FIGS. 18-A, 18-B and 18-C.

FIGS. 18-A, 18-B and 18-C respectively illustrate a carburetor employing an air valve for performing the reset function of the invention with such air valve being illustrated in three selected different operating positions.

FIG. 19-A illustrates a carburetor employing a reset mechanism comprising a profiled shutter for at times partially restricting flow through the associated laminar flow matrix.

FIG. 19-B is a view taken generally on the plane of line B—B of FIG. 19-A and looking in the direction of the arrows.

FIG. 20-A illustrates a carburetor employing a variable venturi as the reset means of the invention.

FIG. 20-B is a view taken generally on the plane of line B—B of FIG. 20-A and looking in the direction of the arrows.

FIG. 20-C is a view similar to FIG. 20-B but illustrating the elements thereof in an operating position different from that of FIG. 20-B.

FIG. 21 illustrates, in cross-section, a carburetor employing a variable area fuel discharge orifice as comprising the reset means of the invention.

FIG. 22 to 33-A shows the new carburetor with different shunts of the laminar flow matrix and the venturi.

FIG. 34 and 35 shows a method to reduce the size of the matrix.

FIG. 36 shows a two-stage application of FIG. 35.

DETAILED DESCRIPTION

Table of Content

1. Terminology, as used in description and claims.
2. Purpose of new carburetor: New metering curves and their advantages.
3. The basic combination of a laminar flow matrix and a reset mechanism which accomplishes these new metering curves. One form of execution (FIG. 6).
4. Idle.
5. Cooperation of new first stage carburetor with second stage carburetor.
6. Means and methods for shaping the metering curves with different laminar flow matrix-venturi combinations:
  - a. Roadload curve
  - b. Transient curves, selection of slant angle.
  - c. Selection of laminar flow matrix.
  - d. Variation of slant angle between members of the family of transient curves.
7. Devices simulating the laminar flow matrix. (Matrix substitute).
8. Selection of best metering suction producing device. (Best laminar flow matrix or matrix substitute-venturi combination).
9. Summary of requirements for metering suction producing devices.
10. Seven reset devices:
  - a. Bypass throttle (FIG. 6).
  - b. Interior discharge throttle (FIG. 15).
  - c. Bleed air valve (FIG. 16 and 17).
  - d. Airvalve (FIG. 18).
  - e. Variable matrix area (FIG. 19).
  - f. Variable venturi (FIG. 20).
  - g. Variable fuel orifice (FIG. 21).
11. Different shunts of the venturi, the laminar flow matrix or its substitute, for accomplishing the transient curves which grow richer with reduced airflow.
  - a. Matrix (or substitute) and venturi in series (FIG. 6).
  - b. Matrix (or substitute) and venturi in parallel (FIG. 22, 23 and 24).
  - c. Matrix in airbleed passage (FIG. 25).
  - d. Matrix controls float bowl vent (FIG. 29 & 33).
12. Matrix controls excessively rich carburetor, with air-dilution by means of interior discharge throttle (FIG. 34, 35 & 36).
13. Conclusion.

1. TERMINOLOGY, AS USED IN DESCRIPTION AND CLAIMS

Wherever terms conforming to the following explanation are INTRODUCED into the description, these terms are capitalized.

In the claims, these terms are capitalized throughout.

1. New Carburetor

The fuel and air metering system according to the invention.

2. Steady State condition or operation

This is the operation at the engine R.P.M. and mixture flow which occurs for each throttle position, in level, constant speed driving. For each throttle there exists a speed in level driving where the total of all moving resistances are exactly balanced by the engine torque delivered at this particular throttle opening and engine R.P.M.. Here all acceleration or deceleration disappear and the vehicle assumes a constant level speed.

3. Roadload curve or Steady State curve (FIG. 1)

A curve plotting fuel-air ratio against mass airflow, as it occurs over the full range from idle R.P.M. with a relatively rich mixture, over LEAN CRUISING, up to full power R.P.M. at wide open throttle with a rich, best power mixture. Going up this curve from idle, BOTH the throttle opening and the engine R.P.M. are increased for each subsequent point. Each point of this Roadload Curve represents one Steady State operating condition.

4. Transient operating condition

An accelerating or decelerating condition which results from leaving the roadload curve through a SUD-DEN change of throttle position. See for instance the lines connecting points I, II, III in FIG. 1. The car has operated at the steady speed of 20 m/h, with 10° throttle opening, at point I. Then the throttle was SUD-DENLY opened to the 35° position, thus disturbing the 20 m/h Steady State and momentarily arriving at the airflow and mixture ratio corresponding to point II. Now, an acceleration with the new constant 35° throttle opening takes place along the curve b. Until this acceleration leads to the next Steady State point III at 60 m/h, a "Transient operating condition" prevails.

5. Transient curves or Constant Throttle-Variable R.P.M. (or Variable Airflow) curves

These are the family of curves (FIG. 1 a, b and c) which plot fuel-air ratio change against airflow change during the just described Constant-Throttle Transient conditions. (In common usage, transient may describe also other changing conditions. In this description, "-Transient curve" is used only in the narrower meaning given above).

6. Lean mixture

A fuel-air ratio which sustains running of an internal combustion engine with some LOSS in torque, but which is NOT yet leaned out to an amount where uneven firing and missing occurs. It is also a mixture strength which gives the minimum of undesirable emission products. With present designs of combustion chamber, such a Lean mixture occurs at fuel-air ratio between 0.056-0.058. The number 0.057 arbitrarily designates in this description this mixture strength. With progress in the art of design of combustion chambers, ignition and stratified charge devices, this particular value may change.

7. Rich mixture

A mixture strength which gives best power, by buying this power increase with higher specific fuel consumption and higher percentage of emission products. Arbitrarily, this Rich mixture is chosen here to extend from 0.062 to 0.070.

8. Excessively Rich mixture

A mixture, usually of a fuel-air ratio above 0.20, which is too rich to operate an engine, and which has to be diluted with a separately controlled air addition to provide the correct Roadload mixture curve.

9. Two Stage carburetor, Primary carburetor, Secondary carburetor

Essentially two carburetors, (usually with common Fuel Level Holding device). The Primary carburetor serves the lower range, from idle to an intermediate power level. This Primary carburetor serves all but the highest power levels of cruising speeds, and is also sufficient for moderate acceleration. This is the carburetor which is calibrated "Lean," for lowest emission numbers and best fuel economy, rather than best power.

The Secondary carburetor joins the Primary carburetor in the higher power range. Especially in its upper range, it is calibrated "Rich" for best power. Because of the unfrequent use of the Second stage, its greater production of emission products and higher fuel consumption can be tolerated.

10. Fuel Level Holding mechanism or device

The Fuel Level Holding mechanism establishes the exact pressure or level of the fuel before it enters the fuel metering orifice. It may consist of a conventional float mechanism, or a fuel spillover, or a diaphragm operated valve.

11. Vent for the Fuel Level Holding mechanism

This is the airconnection to the airspace above the floatlevel of the floatbowl, or to the airspace above the spillover level, or to the dry side of the regulating diaphragm. It establishes the pressure before the fuel metering orifice (together with the hydrostatic head).

12. Main Passage

The passage which receives combustion air, (usually from an airfilter) and receives fuel from one or several fuel metering orifices, either as solid fuel or, if premixed with bleed air, as a foam. The Main Passage discharges the fuel-air mixture into the engine manifold.

13. Main Throttle

The throttle valve which determines the amount of fuel-air mixture flow to the engine, and which is usually connected to the footpedal (or a governor). The Main Throttle is located in the Main Passage.

14. Bypass Throttle

A valved air passage which reduces the metering signal by means of admitting air bypassing the Venturi and/or Matrix or Matrix substitute. (FIG. 6, throttle 8 and FIG. 8).

15. Interior Discharge Throttle

A valved air passage which reduces the fuel-air ratio by admitting additional air downstream of the Main Throttle, directly into the manifold vacuum. (FIG. 15, throttle 91 & FIG. 34, throttle 245).

16. Bleed Chamber (See FIG. 16)

The Bleed Chamber 101 forms a connection or passage between the fuel metering orifice 100 and the discharge port 103 into the Venturi 102. In this chamber, the metered fuel is mixed with Bleed Air.

17. Bleed Air Passage with Bleed Air Orifice (See FIG. 16)

An air passage 108 connecting the Bleed Chamber 101 with an air inlet 104. The Bleed Air Orifice 109 intersects this passage and reduces the Metering Suction according to its flow area.

18. Bleed Air Valve (See FIG. 16)

A valve 105 controlling the flow area of the Bleed Air Orifice 109.

19. Venturi and Air Orifice

Devices which produce nearly square-law relation between air-speed and metering suction.

20. Laminar Flow Matrix or the abbreviation "Matrix"

A device consisting of a great number of parallel, long and narrow airchannels, which produces a pressure drop by means of airfriction on large surfaces (rather than by means of turbulent flow through orifices). This device establishes a nearly linear relationship between pressuredrop through the Matrix and air-speed, at conditions below the critical Reynold number. In the New carburetor, the Matrix is also used close to the critical Reynold number for Mixed Turbulent and Laminar flow conditions.

21. Airvalve

A valved, variable air passage, intersecting the main airstream and located ahead of the Venturi. This Airvalve causes a nearly square-law metering signal curve, of a different magnitude for each Airvalve position. This metering signal AUGMENTS the metering signal produced by the Venturi. (FIG. 18, valve 120).

22. Airvalve, Simulating the Laminar Flow Matrix or the abbreviation "Matrix Substitute"

An Airvalve as defined in 21, except that it is controlled by devices opening it with increasing airflow, in such a manner that it creates a pressure-drop-airflow. relation $\Delta p = C.F.M. > 0.8 > 1.9$ (FIG. 11 & 12)

23. Metering Pressure Drop Δp

If the pressure at the inlet of the metering orifice is kept constant this pressure drop is simply called *Metering Suction*:

The pressure-drop Δp of the air passing through a suction generating device (for instance a Venturi), this pressure drop causing and controlling the fuel flow through a metering orifice.

This pressure-drop or suction will cause the fuel flow through the metering orifice in one of four ways:

1. The suction acts directly on the exit of the fuel metering orifice.

2. The suction is first degraded by means of an air-bleed, before acting on the metering orifice. See FIG. 25. The Metering Suction is here the suction prevailing in the Bleed Chamber 183.

3. The suction acts on a diaphragm-valve combination, or other suction multiplying devices, as known from injection carburetors, this suction being converted into pressure, acting on the inlet side of the fuel metering orifice.

4. Suction acts on the inlet side of the fuel metering orifice, for instance by controlling (directly or indirectly) the pressure in the airspace above the fuel level of a float bowl. (FIG. 29) This suction is always combined with a stronger suction on the exit of the fuel metering orifice, in order to create a Metering Pressure Drop.

24. Metering Pressure Drop Producing Devices or Means

The Devices or Means which cause and control this Metering Pressure Drop Δp .

These may be one of six devices, or mostly a combination thereof.

1. a Venturi

2. an Air orifice

3. a Bleed Chamber (FIG. 25, 183)

4. a bypass passage with connection to the vent (FIG. 29, 202)

5. a Laminar Flow Matrix

6. a Matrix Substitute

10 25. Reset mechanism or device and its Schedule

A device causing a "Scheduled" changing or "Resetting" of the mixture strength. This schedule is determined by the angle of the Main Throttle position.

15 The example of FIG. 6 explains one form of execution: The Main Throttle shaft 4 carries a cam 12 which engages a roller 11, attached to lever 10. Lever 10 operates the Bypass Throttle 8, which bypasses air around the Venturi 3 and/or the Laminar Flow Matrix

20 6. Thus, the shape of the cam determines or "Schedules" the amount of bypassed air, in dependance of the Main throttle opening position. The magnitude of the fuel-air ratio reduction, caused by this bypass air, depends on the cam shape and therewith on Main Throttle positions.

25 Generally, a Reset Device incorporates means to change the fuel-air ratio, either by changing the Metering Pressure Drop, or by diluting the mixture downstream of the fuel discharge, or by using a variable area fuel metering orifice. The Reset Device furthermore incorporates suitable coupling devices between the just mentioned means to change the fuel-air ratio and the Main Throttle. These coupling devices are designed to have the capability to be calibrated to a schedule necessary to achieve the desired fuel-air ratio for each Main Throttle position. Expressed differently, the coupling device between the means to reset the fuel-air ratio and the Main Throttle contains mechanism, (such as cams) which can be calibrated or shaped to coordinate one desired mixture strength value to each and every Main Throttle position.

26. Calibrate and again Schedule

Calibrate means giving the carburetor elements, 45 which determine the mixture ratio, a size which produces the desired fuel-air ratio value.

These elements are the fuel metering orifice, the airflow controlling devices and the Metering Pressure Drop Producing Devices.

50 Furthermore, in the case of the Reset mechanism, calibrate means to assign a fuel-air ratio of its own to EACH Main throttle position, for instance by shaping the cam 12 so as to produce the desired magnitude of the fuel-air ratio correction for each cam position, and therewith for each Main throttle position. Thus, the cam represents in this example the "Scheduling" means which is "Calibrated" to produce individually desired fuel-air ratio values for each Main throttle position.

60 27. C. F. M.

C.F.M. refers here to the Cubic Feet per Minute of combustion air passing through the carburetor to the manifold. When this term is used in an equation, corrective factors for density and constant factors for dimensions are, for simplicity sake, left out of the equation as irrelevant for the understanding of the invention.

2. PURPOSE OF NEW CARBURETOR: NEW METERING CURVES AND THEIR ADVANTAGES

FIG. 1 shows a Steady State Roadload fuel-air ratio curve, with Lean calibration over the cruising range. The additional curves *a b* and *c* are the Transient Constant-Throttle variable R.P.M. curves for conventional carburetors (See Terminology 2-5). These Transient curves are somewhat leaning out, towards their low air-flow end, (or at best maintain a constant fuel-air ratio over some length of the operating range).

The limitation for the leanest possible calibration is imposed by this low end leaning out. For STEADY STATE operation, along the roadload curve alone, it would be acceptable to lower the mixture ratio for cruising considerably under presently used values. However, with such a very lean mixture, lagging and even missing would then occur in TRANSIENT conditions, since transients demand a richer mixture than the steady state condition.

The New carburetor produces a family of constant-throttle variable-R.P.M. curves as shown at *f g* and *h* in FIG. 3, which becomes RICHER at LOW airflows and R.P.M.s. Tests have shown that the constant fuel-air ratio cruising power region of its roadload curve can be lowered to 0.053, and still transient operation without loss in "drivability" be maintained, even without an acceleration pump. In contrast with this, with a conventional carburetor and the same engine, the cruising mixture had to be increased to 0.059 or 0.060 to give comparable transient performance.

The reason for this superiority of the new carburetor is that, whenever steady state driving is interrupted by sudden opening of the main throttle to any greater opening position, the new carburetor with the backwards sloping family of curves *f g & h* at once shifts to operation with increased fuel-air ratio.

FIG. 7 shows the backward slanting transient curves *i j & k* of the new carburetor in more detail. The accelerating example is here repeated with the line I-II-III. The car had been operated with 20 m/h and 10° throttle with the steady state airflow of 15 C.F.M. and an 0.057 fuel-air ratio. Now the throttle is suddenly opened to 35°, and after this movement held steadily in this new position. The mixture flow will, during the sudden throttle opening motion, snap up along the line I-II, to an airflow, of 25 C.F.M., which results from the sudden throttle opening increase WITHOUT R.P.M. change. Therewith, the new airflow of 25 C.F.M. is now combined with the 35° opening, and the mixture ratio increases from 0.057 to 0.062 on the low R.P.M. end of the 35° constant throttle curve *j*. This 0.062 ratio provides maximum torque for the now ensuing acceleration. Now (while the throttle is kept steady at 35°), the car accelerates along curve *j*, until the 60 m/h steady state point III with the airflow of 50 C.F.M. and the economical roadload value of 0.057 ratio for constant speed driving has been reached again.

Thus, while accelerating along curve *j*, the engine is gradually shifted from a best-torque rich ratio to the best-emission lean ratio which occurs at the intersection with the roadload curve. Shortly before reaching point III the engine enters into the region of torque loss, caused by mixture leaning. This creates a built-in self-governing feature which actually prevents the engine from overspeeding into a very lean ratio where un-

tolerable torque loss prevails. Consequently, even on a slight downhill grade, the engine tends to assume the R.P.M. which gives the best operating level, along the constant-throttle variable-R.P.M. curves.

5 During deceleration, the engine will operate on the family of transient curves below the roadload curve, thus leaning out to below 0.057. For the sake of emission reduction, this is a desirable feature.

10 From this it becomes apparent that this novel separation of the roadload curve with lean mixture values on the one hand and of richer transient mixture values on the other hand, brings very great benefits in drivability with a carburetor calibrated to a lean roadload curve.

15 As explained later, the new carburetor permits to select freely the steepness of the backwards slope of the curves *i j k*; if desired, a very slight increase in the fuel-air ratio for reduced airflows can be selected. Also, completely flat curves, with constant fuel-air ratio can be produced. In this case, the new system serves only to 20 compensate for the disadvantage of conventional pure Venturi carburetors to lean out at low speeds.

25 3. THE BASIC COMBINATION OF A LAMINAR FLOW MATRIX AND A RESET MECHANISM WHICH ACCOMPLISHES THESE NEW METERING CURVES ONE FORM OF EXECUTION (FIG. 6)

FIG. 6 shows a simple form of the New carburetor, which accomplishes this desirable separation of the two 30 kinds of metering curves. The drawing shows a Two-Stage carburetor. In this form of execution, only the First stage or Primary carburetor, shown on the right side, is of the design according to the invention, (although the Secondary Stage carburetor can also be 35 designed according to the invention).

The FIRST MAIN element in the New carburetor is a Laminar Flow Matrix, producing a suction which increases in generally linear relation with the airflow, (or other devices of similar pressure drop-airflow relation).

40 This Matrix 6 receives air from an airfilter (not shown). The matrix is arranged ahead of a Venturi 3. The fuel metering orifice 1 discharges into the venturi and is subjected to the Metering Suction composed by the superimposed suctions of the matrix plus the venturi. The resulting mixture passes the Main throttle 5 and is delivered to the engine manifold (not shown) at the carburetor flange.

The metering orifice 1 receives the fuel through a 45 duct 2 from the Fuel Level Holding Mechanism. In the example shown here, it consists of a floatbowl 15, a float 16 which is hinged at the pivot 17 and which operates the fuel inlet valve 18. The Vent 19 connects the airspace above the fuel level with the inlet air of the matrix 6.

The flow resistance of the matrix decreases with 50 reduced airflows LESS than that of a venturi, thus generating a metering suction which does NOT drop off at low airflows as much as that generated by a venturi. Consequently the carburetor, as just described, delivers a mixture which grows richer with reduced main throttle openings. (The effect of the matrix could be compared to that of a choke which is progressively closed as the airflow decreases).

55 This low speed rich deviation of the desired roadload curve is corrected by means of the main throttle controlled "Reset Mechanism." In the example shown in

FIG. 6 this reset device consists of a bypass throttle 8 which moves in an ambient air inlet 7 and which discharges air into the annular plenum space 14, which in turn discharges into the carburetor main passage at the venturi exit. For each opening angle of the bypass throttle 8 the mixture arriving from the venturi is diluted. Thus, with the proper opening sequence of the bypass throttle, the mixture curve can be "reset" to the desired roadload curve.

This required proper opening sequence is generated by the shape of the face of the cam 12, which is connected to the shaft 4 of the main throttle 5. The bypass throttle 8 swings with a shaft 9, which carries the lever 10, which in turn carries the roller 11. A spring 13 forces this roller into contact with the cam face.

With this reset device the bypass throttle opening is controlled and scheduled by the main throttle opening position. The selection of the profile of the cam face permits a free selection of the shape of the roadload curve.

The reset mechanism can be of many different forms of execution, which are discussed in chapter 10. It constitutes the SECOND MAIN element of the new carburetor and is ALWAYS used in conjunction with the matrix (the first main element) or a Matrix Substitute.

The bypass throttle passage can be designed to discharge directly into the carburetor. However the detour of this air discharge through the annular plenum 14 improves the distribution, and the extend of the asymmetry of the plenum and its ring shaped air discharge provides also means to influence the mixture distribution to the manifold.

The metering orifice 1 discharges solid fuel into the venturi. In order to improve atomization, an airbleed circuitry can be fitted to this discharge. The later explained FIG. 26-A gives an example of a bleed arrangement for maximum atomization. The conventional air-bleed system, which are designed to form a compensation, are not needed in the new carburetor, since the matrix fulfills all compensation tasks. The elimination of these conventional airbleeds improves throttle response considerably.

The form of execution of the invention shown in FIG. 6 carries only a single fuel metering orifice. Since one fixed orifice can not cover the entire metering range of an automotive engine, the New carburetor forms here only the Primary stage of a Two-stage carburetor. Since low emission values and low fuel-air ratios are at present of no importance for the upper power range, the Second stage can be of conventional design and is only symbolically represented in FIG. 6, by the body 20, secondary throttle 21, fuel metering orifice 22 and venturi 23.

In order to fully understand the generation of the two kinds of metering curves (discussed in Chapter 2) by means of the new carburetor, it is first necessary to explain the three metering suction curves shown in FIG. 4, which are produced by the three schematically shown carburetors I, II and III, (which do NOT posses the reset mechanism).

The diagram FIG. 4 plots three curves of metering suction against airflow (C.F.M.).

Curve I is the $\Delta P = C.E.M.^2$ the Δ of a purely turbulent venturi, device I.

Curve II is the $\Delta P = C.F.M.$ relation of metering suction created by a matrix of pure laminar flow characteristics.

Curve III finally represents the intermediate relation $\Delta P = C.F.M. > 1 < 2$ resulting from the device III. This is combined of a shorter matrix and larger venturi than shown in I & II, so that the COMBINED pressure drop at maximum airflow equals that of the separate elements I and II.

FIG. 5 plots the fuel-air ratio curves Ir, IIR and IIIr against airflow, as they result from the metering suction curves and devices I, II and III of FIG. 4.

The nearly square-law metering suction curve I of FIG. 4 produces the nearly straight line fuel-air ratio curve Ir of FIG. 5, which (contrary to simplified ideal assumption of being a constant) slants slightly towards a reduced fuel-air ratio for low airflows.

The fuel-air ratio curve IIR (FIG. 5), which results from the metering suction curve II (FIG. 4) of a pure laminar flow matrix, shows the strongest low airflow fuel-air ratio increase.

Finally, the curve IIIr (FIG. 5), produced by the combined laminar flow matrix and venturi used in the new carburetor, exhibits an enrichment at the low airflow end which is intermediate between the pure venturi curve Ir and the pure matrix curve IIR.

Consequently, the desired low-end fuel-air ratio increase can be selected by a fitting combination of the size of the venturi and the laminar flow matrix.

Now returning to FIG. 6, we see that the primary carburetor represented there is identical to the just discussed device III of FIG. 4, EXCEPT for the bypass throttle 8 of FIG. 6. IF this bypass throttle is kept closed, the metering curve k, shown in FIG. 7 is produced, which corresponds to the curve IIIr of FIG. 5. FIG. 7 represents a more elaborate graph of the results obtained with the device of FIG. 6.

The curve k can be produced by TWO methods of changing the air-flow. The first method is to vary the airflow by changing the setting of the main throttle 5, (while the bypass throttle for the purpose of this explanation is still kept closed.) The second method is to hold the main throttle 5 in its wide open position, and change the airflow by means of engine R.P.M. change alone.

It is apparent that the SECOND method of changing the airflow by means of R.P.M. change with constant throttle position indeed produces the desired transient curve k, (as well as the other constant throttle curve i and j, for different smaller constant-throttle positions).

It is furthermore apparent that the FIRST method to vary the airflow by changing the throttle position (with the bypass valve closed), results in an utterly wrong roadload curve of a shape also following curve k.

Without additional corrective devices (that is with the bypass throttle 8 closed), the roadload curve simply coincides with curve k; the metering suction depends on the magnitude of airflow only, and will assume the same values, regardless whether the airflow is changed by means of throttle position changes or engine R.P.M. changes.

This is where the use of the Reset device comes in, in order to separate the two kinds of metering curves, as described in Chapter 2 as the aim of the invention. The bypass throttle 8 with its scheduled cam connection to

the main throttle shaft 4 fulfills this aim. Each airflow point of the uncorrected curve k is lowered to the desired mixture strength of the roadload curve, by means of a fitting opening of the bypass throttle 8.

The carburetors diagrammatically shown respectively in FIGS. 7-A, 7-B, 7-C, 7-D, 7-E and 7-F are a repeat of the carburetor of FIG. 6, for six different load conditions, each corresponding to one point of the roadload curve. These figures show the relation between the openings of the two throttles.

The new carburetor system of the primary stage covers the cruising range from 5 C.F.M. at idle to 120 C.F.M., which is the airflow at the top of the economical part load operation. From 15 to 120 C.F.M., this primary stage carburetor is calibrated to a roadload curve with the most economical ratio of 0.057. Over this entire range, the secondary, conventional carburetor remains closed.

Beginning at point I of the roadload curve of FIG. 7, the main throttle of FIG. 7-B is correspondingly illustrated at the 10° position. The bypass throttle is almost completely open, since the bypass has to provide here the largest mixture correction from the corresponding airflow point of the curve k . (It is to be remembered that the laminar flow matrix WOULD produce a roadload curve similar to the transient curve k , IF the bypass throttle would not be opened).

Next, as illustrated in FIG. 7-C, the throttle is opened to the 35° position. If very gradually opened, the car just increases speed with the mixture ratio given by the roadload curve. If, on the other hand, the throttle is suddenly opened, and then kept steady at the 35° position, the mixture ratio follows (as explained previously) the points I-II-III, with an increase of the fuel-air ratio to 0.062 at point II, and a gradual return to 0.057, after accelerating up to the balanced point III at the intersection with the roadload curve.

The carburetor picture of the 35° throttle position shows that the bypass throttle opening is here considerably reduced. The reason is, of course, that the needed mixture strength correction from the corresponding point of the curve k is now less than that at the previous 15 C.F.M. 10° throttle point.

Now, going further up the roadload curve, the wide open throttle position (of the new primary carburetor) is finally reached as generally depicted in FIG. 7-D which, in turn, corresponds, for example, to an air flow, in FIG. 7, of 120 C.F.M. The corresponding picture of FIG. 7-D shows that the bypass throttle is here completely closed. The reason is that the curve k , produced by the combined matrix and venturi generated metering suction, without bypass correction, intersects the roadload curve here.

An R.P.M. change from this open throttle position, be it during a previous acceleration, or when entering a grade, will result in fuel-air ratio changes along the curve k , since, with constantly open main throttle position the bypass remains closed.

It is apparent that the amount of correction created by the bypass throttle openings depends on the profile of the cam 12 which positions the bypass throttle. It follows that the selection of this profile permits the selection of any desired shape of a roadload curve.

This detailed explanation gives the corrective relation between main throttle opening and bypass throttle

opening, which results in the lean roadload curve. It also shows the enriching effect of operation at R.P.M.s which are lower than the R.P.M.s of the corresponding roadload throttle opening; with these reduced R.P.M.s, the bypass throttle position is at the smaller opening, assigned to the higher main throttle opening. The picture FIG. 7 shows that the movement of the two throttles (the primary carburetor throttle valve and the bypass throttle valve) is essentially opposed, over the constant 0.057 mixture range.

4. IDLE

Once more returning to the roadload curve, a closing of the main throttle from 10° to a 2° or 3° position as depicted in FIG. 7-A brings the carburetor delivery into the idle range. Roadload curves for this region are always calibrated to become richer, somewhat according to the shape shown in FIG. 7.

Conventional carburetors need the added fuel supply from a separate idle system.

It is a great advantage of the new carburetor that it does not need an idle orifice, but that it can supply any degree of richness in the idle range with the main orifice alone. This is simply done by closing the bypass throttle (which was almost completely open in the previous 10° position) when the main throttle is closed to the 2° or 3° idle position. The closing schedule and the amount of closing of the bypass determines the steepness of the fuel-air ratio curve between 15 and 5 C.F.M., as well as the amount of idle enrichment.

The idle mixture adjustment is obtained by changing the bypass throttle position at idle, by means of a variable end of the cam, or an overriding mechanism

A further great advantage of the elimination of the conventional idle system is the lack of the troublesome and sensitive fading-out of the idle orifice and fading-in of the main orifice, at the beginning of the cruising range. Accurate metering in this region is much more easily obtained with the single orifice system of the new carburetor.

5. COOPERATION OF NEW FIRST STAGE CARBURETOR WITH SECOND STAGE

At the high airflow end of the roadload curve of FIG. 7, from 120 C.F.M. to full power, the secondary carburetor throttle opens, while the primary carburetor throttle remains in its open position as generally depicted in FIGS. 7-E and 7-F.

In conventional carburetors, the secondary stage can NOT be of the simple basic design, shown in FIG. 6, since its fuel-air ratio curve leans out at low secondary throttle openings. In order to prevent a "hole" in the region where the secondary opens, a great variety of compensation mechanism are employed.

Furthermore, frequently a powervalve has to be opened during the second stage operation, in order to produce the needed wide open, best power, rich operation.

The new primary carburetor in its cooperation with the secondary stage, offers the great added advantage of eliminating such "crutches" for the second stage, for the following two reasons:

Firstly, when the second stage throttle opens, the manifold suction drops and therewith the airflow through the primary, Laminar Flow stage is reduced.

This airflow reduction for the constant wide open primary throttle has the SAME effect as an airflow reduction caused by engine R.P.M. reduction; the primary carburetor reduces its delivery according to curve *k*, and consequently its fuel-air ratio increases. Thus, this increase can make up for the drop in fuel-air ratio caused by the low flow delivery of the conventional secondary stage.

Second, the reset mechanism can also be used to correct the part throttle leaning out of the secondary stage. Furthermore, this primary reset mechanism replaces the conventional power valve. The sequence of throttle positions for 120 C.F.M., 170 C.F.M. and 240 C.F.M. of FIG. 7, and as correspondingly depicted in FIGS. 7-D, 7-E and 7-F, explains these compensations.

At 120 C.F.M., the top of the primary range, the bypass throttle is completely closed.

At 240 C.F.M., the wide open position, the bypass throttle is also closed. In order to obtain an 0.070 "rich" fuel-air ratio, without the help of a powerjet, an accordingly large fuel orifice (22 in FIG. 6) is employed.

Going now down to the 170 C.F.M. position, the wide open 0.070 ratio would then be undesirably high. Here, with conventional carburetors, the powervalve would close off and reduce the fuel flow to, for instance, an 0.061 ratio.

With the help of the bypass throttle, this is now possible WITHOUT a powervalve. The bypass throttle 8 can be operated by means of a main throttle dependent cam, or (better) by means of a manifold vacuum sensitive diaphragm, opening it to the selected intermediate position shown in the drawing, thus reducing the ratio to the desired 0.061 level.

Going further down to the 130 C.F.M. region, where the secondary throttle is just cracked open and delivers only a very small airflow, the fuel-air ratio of the conventional secondary stage may fall off to very lean values. To avoid this, it is only necessary to schedule the reset mechanism in such a way that the bypass throttle again is returned into its closed position, thus pushing the ratio to higher values. This closed position is then maintained when going further down to 120 C.F.M., the top of the primary range, where the secondary carburetor ceases to work.

Thus, the reset mechanism of the NEW primary carburetor can be used to give to the roadload curve delivered by the secondary, CONVENTIONAL stage the best desired shape.

6. MEANS AND METHODS FOR SHAPING THE METERING CURVES WITH DIFFERENT LAMINAR FLOW MATRIX - VENTURI COMBINATIONS

a. ROADLOAD CURVE

The dependance of the roadload curve from the cam shape makes it possible to calibrate the roadload curve of the new carburetor to almost any desired shape (See chapter 3).

b. Transient Curves, Selection of Slant Angle

As briefly explained before, the slant angle of the constant-throttle variable-R.P.M. curves can also be freely selected. For instance, in order to obtain a transient curve of reduced steepness, it is only necessary to select a shorter matrix of reduced pressure drop,

and then replace the pressure drop reduction with a suction increase derived from a smaller venturi. With this procedure, even almost flat transient curves can be created (where the short laminar flow matrix only corrects for the low airflow leaning-out). This may be desirable for engines operated with a great variety of R.P.M.s, such as aircraft engines, where transients are of lesser importance. Even with such flat curves, the new system is still superior to conventional carburetors, since conventional carburetors exhibit curves sloping entirely in the wrong direction (leaning out at low flows). Indeed, the basic elements of the new carburetor are all retained, even with flat constant-throttle variable-R.P.M. curves. Only the size of the Laminar Flow component and the bypass throttle passage is reduced.

c. Selection of Laminar Flow Matrix

A Laminar Flow Matrix supplies a strictly linear relation between airflow and pressure drop for slow airspeeds only (produced with a large matrix area), at a Reynold number under 600. For small-area laminar elements, with higher Reynold Numbers, an exponential distortion is increasingly added, until at (or before) the Reynold number 2,000 almost purely turbulent flow prevails.

In the new carburetor the linear airflow-suction relation of the matrix is anyhow degraded, by means of the added venturi. Therefore it is not necessary to use a very large matrix with pure laminar flow. Rather, a smaller matrix, with PARTLY linear and partly turbulent characteristics, close to the Reynold number 1,500 at maximum airflow can be selected, thus taking over part of the function of the venturi. The venturi should then be chosen with an accordingly larger throat, since the matrix takes over part of its turbulent function. In some cases, the venturi can thus be eliminated altogether, and the matrix alone serves the purpose of creating an intermediate suction-airflow relation, according to curve III of FIG. 4.

In some applications, the matrix can be sufficiently small to enter an almost entirely turbulent flow area at the top of the primary range, if the roadload curve is shifted here anyhow to richer best power ratios. To summarize: A pure Laminar Flow Matrix has a relation of $\Delta P = C.F.M.$

A purely turbulent Venturi has a relation of $\Delta P = C.F.M.^2$.

The Laminar Flow Matrix serving the new carburetor should, over the major portion of the lean part of the roadload curve, remain in the range of values $\Delta P = C.F.M. > 1 < 1.9$

d. Variation of Slant Angle between Members of the Family of Transient Curves

The new carburetor also offers the possibility to select transient curves of a steepness which vary for different main throttle positions. For instance, the slope of curve *k* in FIG. 7 can be reduced to the dashed line, by selecting a smaller matrix which has a larger turbulent component in the upper airflow region.

It is also possible to use a movable shutter (135 in FIG. 19) which blanks off part of the matrix area, and which is moved and controlled by the main throttle. (This device is more fully explained in Chapter 10 and FIGS. 19-A and 19-B). By proper scheduling of the shutter movement, and therewith the area reduction of

the matrix, any desired distribution of steepness of the slope of the family of transient curves can be obtained. Since such a reduction of the matrix area also influences the roadload curve, this influence must be compensated by scheduling the bypass throttle accordingly.

It is also possible to combine a variable venturi with a constant matrix area, and control the venturi throat area variation from the main throttle.

The use of the just described additional mechanism for influencing the slant angle distribution can be avoided by using different combinations of shunting the reset bypass channel into the main airflow. The influence of these different shunt combination will be explained in Chapter 11b, as these different devices are discussed. As an example it shall suffice here to explain the device shown in FIGS. 8-A, 8-B and 8-C.

This primary carburetor is identical to the primary stage shown in FIG. 6 and 7, except for the location of the discharge of the bypass airflow into the main stream. In FIG. 6 and 7 the discharge takes place BEHIND the venturi. In FIG. 8 the bypass throttle discharges AHEAD of the Venturi. FIGS. 8-A, 8-B and 8-C respectively show three opening positions for 15, 50 and 120 C.F.M. In the 120 C.F.M. position where the bypass is closed, both the devices of FIG. 7 and FIG. 8-A give obviously the same curve *k*. For lower airflows however, where the bypass throttle opens, a difference in the slope of the curves will result. The shunting of the carburetor (as depicted in FIGS. 8-A and 8-B) produces the dashed, flat angled curves *m* and *n*, (while *k* remains on the solid line) since a larger percentage of air traverses the square law venturi in these positions, thus diminishing the percentage of the contribution of the laminar flow matrix (which was the cause of the low-end fuel-air ratio increase). Of course the reset mechanism, (that is the shape of the cam driving the bypass throttle) has to be made to match the new conditions.

7. DEVICES SIMULATING THE LAMINAR FLOW MATRIX (MATRIX SUBSTITUTE)

As explained previously, the purpose of the Laminar Flow Matrix in the new carburetor is to create a suction which rises proportional to the airflow, or provides a suction curve somewhere halfway between a linear relation and a square relation to the airflow.

It is possible to simulate such a curve with airvalves which are opened and closed on a schedule generating a linear relation between airflow and pressure drop through this valve. This can be done by means of a device translating a suction signal into positioning of the airvalve, for instance by means of a diaphragm.

It is however also possible to accomplish a nearly linear airvalve created suction curve by means of springloaded valves or hinged flapper valves. Four forms of execution shall be described here-after. These valves are designed to replace the laminar flow matrix, for instance the matrix 6 in FIG. 6.

FIG. 9 shows a simple springloaded plate valve taking the place of the matrix in the new primary stage carburetor similar to that of FIG. 6. This device creates the pressure drop ΔP in the air duct 32-33 by means of the spring 31. The tension of this spring rises proportional to the valve opening, starting with ZERO tension when

the valve is just closed. Zero tension for the closed position means NO BIAS spring load.

FIG. 10 shows the suction-airflow relation obtained with such a valve and spring load. This curve is compared with a venturi curve and a laminar flow curve. It can be seen that the springloaded valve curve raises the low-end suction even more than a laminar flow matrix.

The total stroke for this valve is short. Therefore the spring rate has to be steep, and the spring has to be manufactured and positioned to very close tolerances.

FIG. 11 shows another design of an airvalve which approaches the linear pressure drop airflow relation of a matrix.

This airvalve consists again of an air duct 35-36, a floating valve 37 and a tension spring 38 of linear characteristic, which is attached to the air duct by means of the rod 39. This spring is of a much lower spring rate than that of FIG. 9, since the valve stroke is larger.

In the closed position of the valve 37 (dashed lines), the spring exerts again zero tension (no bias load). Under the influence of an airflow, the valve moves down and assumes a balanced position where the opening between the valve and the conical portion of duct 40 creates an airspeed, and therewith pressure drop, balancing the spring-tension for this particular valve opening.

The resulting pressure-drop airflow-relation is similar to that shown in FIG. 10 (for a straight conical section 40). The low rate spring is easier to manufacture to close tolerances than that of FIG. 9. Also the condition of zero bias load in the closed position is easier to maintain.

A further advantage of the design of FIG. 11 is its complete lack of friction, an extremely important feature for a mechanical device designed to replace the laminar flow matrix.

As explained before, and as FIG. 10 shows, the suction-airflow relation of this device creates even higher suctions at low airflows than the linear matrix. If this valve replaces the matrix 6 of FIG. 6, its higher suction generation at low airflows will create steeper transient curves *i*, *j* and *k*. In order to reduce the slope of these curves, the equivalent procedure as described in chapter 6b has to be used; it has been explained there that a shorter matrix, creating a smaller linear component of the total metering suction, is used, and the venturi throat narrowed down to a value where the venturi replaces the metering suction lost through the shortening of the matrix. Thus the total metering suction is maintained, but the linear component and consequently the amount of low speed enrichment reduced.

The equivalent procedure for the device of FIG. 9 and 11 is to reduce the springrate and again replace the therewith reduced metering suction by means of a smaller venturi throat.

The foregoing shows that a special air valve, replacing the laminar flow matrix, does NOT have to duplicate a linear flow relation very closely. The devices of FIG. 9 and 11 are actually overdoing the effect of laminar flow matrix, with a relation approximating the equation $\Delta P = C.F.M.^{0.8}$; they increase the low airflow enrichment even stronger than a pure linear Matrix. Yet, these devices are perfectly suited to

produce transient curves which are close to the curves *i*, *j* and *k* of FIG. 7. This is done by the simple expedient of reducing the airvalve-produced percentage of the total metering suction generation of the airvalve-venturi combination.

The criterion for the design of an airvalve simulating the effect of a matrix is simply a relation of $\Delta p = C.F.M. > 0.6 < 1.9$. As long as the exponent is less than the "two" exponent of a purely turbulent venturi, some low airflow enrichment is obtained. This is the same condition as explained in chapter 6c, "Selection of Laminar Flow Matrix," except that the airvalve can create a relation with an exponent smaller than "ONE," something which a laminar flow matrix can not accomplish, but which, as explained before, is usable for an accordingly selected airvalve venturi combination.

Consequently, the described airvalve indeed simulates the laminar flow matrix, AS USED in the new carburetor, namely in combination with a venturi.

In some cases it may, however be preferable, to simulate the straight line relation of a low Reynold number matrix more closely. FIG. 12 shows how this can be accomplished with a device almost identical to that of FIG. 11. The only difference is that the wall portion 41 of FIG. 12 is curved, rather than conical as in FIG. 11.

The curvature of the portion 41, in which the valve moves, determines the pressure drop-airflow relation. In the previously described device of FIG. 9, the flow area was (closely) proportional to the valve travel and therewith the tension of the (linear) spring. With the device FIG. 12, however, the throttling gap between the valve and the wall 41 depends on the profile of this wall. By means of the selection of this profile, any desired transient fuel-air ratio curve can be generated. The profile shown in FIG. 12 is designed to give an almost straight line relation between suction and airflow.

An improvement of the Matrix suction simulating device of FIG. 11 is shown in FIG. 13. This device takes over the function of BOTH the matrix and venturi.

FIG. 13 shows schematically a complete primary carburetor, generating the same mixture curves as shown in the curves of FIG. 7.

The carburetor air inlet 50 connects to the venturi throat 53. The main throttle 55 controls the mixture flow to the carburetor outlet 52. The reset device consists again of the bypass throttle 68, the throttle shaft 69, the lever 60 attached to this shaft, and the roller 61 attached to the free end of this lever. Roller 61 is pulled by spring 63 against the face of the cam 62, which is rotated by the main throttle shaft 54.

The function of this reset device is the same as with FIG. 6. It discharges the reset air into the circular duct 67, where it joins the mixture coming from the Venturi 53.

The combination of the laminar flow matrix simulating valve and the venturi is accomplished by means of the floating valve 56. As a valve it functions similar to the device of FIG. 11; it is suspended on a linear spring 59 which attaches by means of the rod 60 to the carburetor inlet wall 50.

Again, the springtension must be zero in the position of smallest flow area and increases in a linear function up to the stretch which creates the maximum intended pressure drop at the maximum downtravel of the valve 56.

Contrary to the device of FIG. 11, the valve of FIG. 12 is streamlined, thus affording the great advantage of suction recovery.

In the previous device of FIG. 11 the valve only replaces the matrix of FIG. 6. There, the fuel discharge takes place downstream of this valve. A streamlined recovery with this design is impossible, since it would eliminate ("recover") the very metering suction this valve is designed to create. The problem of a solution to the contradictory requirement of needing the valve-created suction and advantage of suction recovery is solved with the device of FIG. 12.

Here the fuel is discharged through the metering orifice 71, into an airbleed flow admitted at the bleed orifice 57. The resulting foam is discharged at the valve periphery, that is the points of highest suction, through radial holes 58.

The orifice 71 receives the fuel from a conventional float mechanism (not shown) which connects to the nipple 70. This stationary nipple connects by means of the highly flexible hose 72 to the metering orifice 71.

It can be seen that the fuel foam discharge travels with the downwards moving valve, always discharging at the narrowest ring area formed for each valve position, thus sensing the highest metering suction created by the valve and by the flared-out valve seat 51, for each valve position. The figure illustrates how the valve, and "valve seat" 51 combine to form a venturi recovery.

To summarize: In FIG. 13, the function of the laminar flow matrix is simulated by the valve 58, its spring 59 and its profiled valve seat 51. At the same time, the venturi portion of the metering suction is created in the same device, by means of the streamlined valve 56 and the venturi 53-51. This device gives the advantage of simplicity and suction recovery. The suction recovery, of course, extends the operating range of this primary stage carburetor.

It was previously explained that the springs for the valves of FIG. 9, 11, 12 and 13 have to give zero tension in the closed position, in order to create the matrix suction curve simulation.

This requirement can however be modified to a very slight degree, by giving this valve a constant "bias" tension, in its closed position. This tension should be just enough to help to create the needed rich idle mixture. For a single orifice primary stage carburetor, this bias should normally be in the order of only 1 inch water. This bias-tension can be made changeable, for adjusting the idle mixture strength.

Still another springloaded airvalve design is shown in FIG. 14. This valve, is also designed to replace the laminar flow matrix 6 of FIG. 6.

The valve is formed by a leafspring 83, which, in its relaxed position, blanks off almost the entire airinlet to the valve body 80. This leafspring-valve 83 is attached to the body by means of screws 84.

As the airflow increases, the leafspring is deflected towards an open position. The spring rate changes during this opening movement, by developing the leaf spring over the profile 81 of the valve body. The selection of this profile makes it possible to vary the airflow-pressure drop relation.

A further help in the selection of this curve is given by the profile of the wall 82. Just as in the case of the

valve shown in FIG. 12, this profile determines the amount of opening assigned to each increase in spring tension.

Thus, there are two ways to influence the suction curve of this valve, making a close simulation of a laminar flow matrix possible.

As pointed out before, spring loaded airvalves are known in the art. However, they have been used only to create changes in the metering curves as shown in the graph of FIG. 2.

According to the invention, these airvalves are used IN COMBINATION with the reset mechanism, thus creating the desired separation between the shape of the roadload curve and the family of transient curves. Even though the airvalves of the new carburetor may possess the same basic components as known airvalves, (such as a valve and a springload), they have to differ from conventional airvalves in the magnitude and relation between spring characteristic and valve opening, in order to create the suction airflow curve which simulates the laminar flow matrix, demanded by the invention.

8. SELECTION OF BEST METERING SUCTION PRODUCING DEVICE (BEST LAMINAR FLOW MATRIX OR MATRIX SUBSTITUTE - VENTURI COMBINATION)

Tests with the new carburetor have shown that, for the average automotive engine, a moderate backwards slope of the family of constant-throttle variable-R.P.M. curves is desirable. For instance, it has been found that good transient response has been obtained when curve *j* starts (at the low end) with a ratio of 0.062, for 20 C.F.M., and then drops to the roadload ratio of 0.057 at 50 C.F.M.

A steeper curve gives almost no further improvement in transient response, but can increase the fuel consumption and emission numbers when driving off the roadload curve, for instance on a grade.

Basically, it is desirable to select the smallest low R.P.M. enrichment, where good transient response, together with a lean roadload curve is still possible.

In chapter 3 it has been shown that a pure Laminar Flow Matrix (curve *IIr* of FIG. 5) gives the largest low end enrichment. This enrichment is so high that in all but very exceptional cases a degradation of the laminar flow effect is necessary, in order to arrive at the curve *IIIr* (equivalent to curve *k* of FIG. 7) which is somewhere in between a curve generated by a venturi alone (curve *Ir*) and the pure laminar flow created curve *IIr*.

In chapter 6 *b* and *c* it was established that this degradation of pure laminar flow generated metering signal can be done by one of two methods, or a combination of both: The first method is to combine a venturi and a pure laminar flow matrix. The second method is to use a laminar flow matrix alone, which comes close to the critical Reynold number, thus generating a mixed turbulent and laminar flow suction curve. The best practice is to combine both methods, that is to combine a venturi with a not completely linear matrix, thus generating a suction-airflow relation which, according to the engine, is selected to be higher than $\Delta p = C.F.M.$, but lower than $\Delta p = C.F.M.^2$. A good value is for instance $\Delta p = C.F.M.^1.8$. However,

since the exponent changes as the airflow increases to higher Reynold numbers at higher airflow, a compromise range of value for each of the family of transient curves has to be established by experiments.

This explanation of the difficulties and rather wide range of selection possibilities shows that it is impossible to define the invention to any particular, or even narrow range of combination of the means creating a linear and a square metering suction curve. The aim of 5 the new carburetor is to create good transient response over the lean part of the roadload curve. This can be obtained as long as the metering suction airflow relation has an exponent which is LESS than square. Consequently, the only valid definition for the COMBINATION 10 of the Laminar Airflow Matrix, and the Venturi, is a relation of $\Delta p = C.F.M.^{1.2 < 1.9}$. Over the lean roadload range of carburetor, the values of this exponent will vary between these limits, and the best compromise will have to be found by a combination of 15 the methods and means described in Chapter 6.

The circumstances are further complicated by the possibility to replace the laminar flow matrix by a special airvalve which simulates laminar flow conditions, as described in Chapter 7. These devices are independent of an approach to a critical Reynold number with larger airflows. Furthermore, with proper choice of the profiles (FIG. 12) or change of spring-rate (FIG. 14), the exponent can be more freely selected than with a laminar flow matrix. Consequently, with the use of 20 these devices, the proper intermediate exponent between 1.2 and 1.9 can be simulated with or without the combination with a venturi.

9. SUMMARY OF REQUIREMENTS FOR METERING SUCTION PRODUCING DEVICES

It is possible to combine a laminar flow matrix of lower Reynold number with a venturi, or to use a higher Reynold number matrix alone. It is also possible 40 to combine laminar flow simulating airvalves with a venturi, or equip these airvalves with opening profiles which deliver the desired intermediate value without a venturi. The common criterion for these COMBINATION 45 of the Laminar Flow Matrix, or its Matrix Substitute, with a Venturi (which may be included in the Matrix or Airvalve) is: "METERING SUCTION GENERATING DEVICES WHICH, OVER THE LEAN PORTION OF THE ROAD LOAD RANGE FOLLOW THE RELATION $\Delta p = C.F.M.^{1.2 < 1.9}$ ". The most desirable values are $\Delta p = C.F.M.^{1.7 < 1.9}$, which are the values to be approached in the most frequently used driving range. These values give good transient response, without excessive full consumption during acceleration and/or grade driving, and these values require the use of the reset device according to the invention, in order to level the roadload curve down to the best desired shape.

A combination of a laminar flow matrix with a venturi constitutes the most reliable metering suction generating device, since there are no moving parts subject to wear and no spring which can lose the calibrated value.

A combination of a laminar flow matrix simulating airvalve with a venturi is smaller and cheaper, and gives good results in the new carburetor IF designed without friction and with closely calibrated, unchanging 65 springs.

10. SEVEN RESET DEVICES

a. Bypass Throttle (FIG. 6)

This reset device has been fully described in chapter 3 and FIG. 6, 7 and 8.

b. Interior Discharge Throttle (FIG. 15)

FIG. 15 shows this reset device schematically. All parts are identical to those of FIG. 6, except the location of the discharge 90 of the reset throttle 91, which discharges DOWNSTREAM of the main throttle 92.

The reset function is accomplished by controlling an air admission directly into the manifold vacuum, by means of the throttle 91, which dilutes the mixture and therewith reduces the fuel-air ratio.

The scheduling mechanism, which connects the main throttle to this reset throttle, is similar to that shown in FIG. 6 and therefore not again explained.

c. Bleed Air Valve (FIG. 16 & 17)

FIG. 16 illustrates the first form of execution of this reset device. The fuel orifice 100 discharges into a Bleed Chamber 101, which in turn discharges into the venturi 102, by means of the somewhat larger discharge port 103. This mixture chamber receives ambient bleed air from the bleed air inlet 104, by means of the Bleed Air Passage 108. A valve intersects the bleed airflow. This valve is formed by a tapered metering rod 105, which varies the Bleed Air Orifice by means of axial movement. This metering rod is operated by the main throttle 106, by means of a scheduling mechanism consisting (for instance) of a cam 107 and suitable devices connecting this cam to the main throttle.

The fuel-air ratio is reduced according to the amount of bleed air admitted to the chamber 101. The "reset" function is therewith accomplished by the Bleed Air Valve 105.

FIG. 17 a and b show another form of execution of a bleed-air valve. All parts are identical to those of FIG. 16, except for the design of the bleed air valve itself.

The bleed air passage 114 connects again to the bleed chamber 110. It is intersected by a plate valve 115, which is shown in side view in FIG. 17b. This plate valve is connected by means of the shaft 117 to the main throttle 116. It carries a profiled slot 118, which registers with the duct 114. The choice of the profile of the slot 118 permits a free selection of the schedule of the bleed air opening in relation to the main throttle opening.

d. Airvalve (FIG. 18)

FIGS. 18-A, 18-B and 18-C illustrate schematically how the reset function can be accomplished by means of an airvalve 120, located upstream from the venturi 122. (This airvalve could also be located ahead of the matrix 123.) Again, this reset valve 120 is connected to the main throttle 124 by means of a scheduling mechanism, for instance similar to the cam mechanism shown in FIG. 6, (and therefore not repeated in FIGS. 18-A, 18-B and 18-C), but with a different cam shape.

The resetting, of the fuel-air ratio curve N to the roadload curve is done by PARTLY closing the duct of the airvalve 120 when the curve has to be pushed up. The graph of FIG. 18 illustrates the relationship of the three throttle positions of the airvalve carburetor of FIGS. 18-A, 18-B and 18-C. It shows that the resetting of the curve N is done by INCREASING the fuel air ratio by means of the airvalve, rather than decreasing it (with the bypass throttle, for instance), as was done with all previous reset devices.

The size of the fuel orifice and of the metering suction generating devices is selected to generate the "natural" curve N, IF the airvalve is left open. The three positions of the main throttle and airvalve show how the roadload curve is obtained by partly closing the reset airvalve as, for example, illustrated by points X and Y in FIG. 18 corresponding to FIGS. 18-B and 18-C, respectively.

Airvalves for conventional carburetors are used to increase the fuel-air ratio at low airflows; the airvalve is partly closed at low airflows, and is opened at higher airflows. The coupling between the main throttle and the airvalve of these known carburetors produces the exact OPPOSITE opening relation between the two throttles, than that used in the new carburetor.

The reason is as follows: In conventional carburetors an airvalve is used to compensate for the leaning out of the fuel-air ratio at low airflows. In contrast to this, in the new carburetor, the matrix already more than accomplishes this compensation. The airvalve is here used to reduce the overcompensation created by the matrix. As with the other reset devices of the invention, it accomplishes its task only in combination with a matrix.

e. Variable Matrix Area

FIG. 19a, shows the sections through a carburetor with reset mechanism, consisting of a profiled shutter blanking off the laminar flow matrix. FIG. 19b shows the side view of this shutter.

The inlet air from the matrix 133 passes to the venturi 132 and the main throttle 136. The main throttle shaft 137 carries the plate valve 135, which is fitted with a profiled edge 138. The selection of the edge profile determines the amount of resetting, and therewith the shape of the roadload curve.

The function of this reset device is similar to that of the preceding airvalve, except that the blanking off of the matrix not only influences the roadload curve, but also influences the steepness of the slope of the transient curve. A combination of the variable matrix area reset mechanism with one of the other reset mechanism will yield the best shape for both kinds of metering curves.

f. Variable Venturi

The three drawings of FIGS. 20-A, 20-B and 20-C illustrate a variable Venturi reset device. FIG. 20-B is the section B-B through FIG. 20-A. FIG. 20-C shows the device in a part load throttle position.

The venturi 142 is movable in axial direction inside the carburetor body 141. The fuel orifice 140 is subjected to different metering suctions, according to the venturi position, as exemplified by the positions of the elements in FIGS. 20-B and 20-C. The main throttle 146 is coupled to a cam 147, which engages a roller 145. This roller is connected to the movable venturi by means of the shaft 148.

The profile of the cam 147 determines again the reset schedule for the effective venturi suction, and therewith the roadload curve.

It is also possible to use a movable fuel discharge, together with a stationary venturi. As long as the fuel orifice discharges into different areas of the venturi, on a schedule determined by the main throttle, the variable venturi reset effect is obtained, regardless of whether the venturi is movable and the fuel discharge

stationary, or whether the Venturi is stationary and the fuel discharge displaced along the axis of the Venturi.
g. Variable Fuel Orifice (FIG. 21)

In this reset device, all airflow metering means are constant. Instead of changing the metering suction, as in all previous devices, a variable fuel orifice serves to reset the fuel-air ratio to the correct roadload curve.

The fuel orifice 150 is controlled by the tapered metering rod 155, which is moved in axial direction by the profiled cam 157. This cam is rotated by the main throttle 151, by means of a suitable leverage system.

Many variations of the illustrated reset devices and the manner in which they are driven by the main throttle are possible, without altering their basic function.

11. DIFFERENT SHUNTS OF THE VENTURI, THE LAMINAR FLOW MATRIX OR ITS SUBSTITUTE, FOR ACCOMPLISHING THE TRANSIENT CURVES WHICH GROW RICHER WITH REDUCED AIRFLOW

a. Matrix (or Substitute) and Venturi in Series (FIG. 6)

This form of execution of the invention has been explained in Chapter 3.

b. Matrix (or Substitute) and Venturi in Parallel (FIG. 22, 23 and 24)

FIG. 22 shows an execution of the invention which is identical to that of FIG. 6, except that the Laminar Flow Matrix 160 and the Venturi 161 are shunted in parallel. The fuel metering orifice 162 receives the fuel from a float level holding device (not shown). The matrix discharges into channel 166, which connects to an annular plenum 164. The plenum discharges on the periphery of the venturi exit 167. Even more than in the carburetor of FIG. 6, the extent of asymmetry of the annular plenum 164, as well as a possible asymmetry of the ringshaped exit of this plenum into the main mixture stream provides means to influence the mixture distribution to the manifold.

The bypass throttle 165 constitutes the reset device, and is controlled by the main throttle 163, in the manner explained in FIG. 6 and Chapter 3.

The low airspeed mixture enriching effect of a parallel shunted matrix and venturi shall now be explained:

The parallel matrix delivers air at the venturi exit, diluting and leaning out its very rich mixture delivery. When the carburetor flow is reduced, for instance through R.P.M. reduction, the flow-resistance of the venturi decreases MORE than that of the matrix. Consequently, of the total carburetor flow, the percentage of diluting air, which passes the matrix, decreases relative to the percentage of venturi derived mixture, thus causing a low speed enrichment similar to that produced by the series shunting device of FIG. 6. Again, the relative flow areas of the matrix and venturi determine the slant angle of the low speed enrichment of the transient curves.

Generally, the same consideration concerning the relative size of the matrix and the venturi for the shaping of the metering curves, as discussed in chapter 6, also apply to the parallel shunted metering suction producing device. Also, the feasibility to replace the matrix with a laminar flow simulating airvalve applies to the parallel shunted device.

FIG. 23 shows the combination of the same parallel shunted metering suction producing devices with a modification of the bypass throttle reset device.

Here, the reset throttle 175 does NOT admit ambient air, but receives its air also from the laminar flow matrix 170. The reset throttle can close the passage 176 only PARTLY. The constantly open portion 178 of the passage 176 always communicates with the annular plenum 174. Thus, this constantly open passage 178 fulfills the purpose of the passage 166 of FIG. 22, generating the matrix correction of the transient curves over the entire range.

As far as the Reset function of the bypass throttle 175 is concerned, the fact that the bypass air flows first through a matrix makes no other difference than that the cam driving the throttle 175 has to be shaped to give the bypass throttle more opening. For instance, if a 30° opening of the bypass throttle 165 of FIG. 22 is sufficient to give the proper fuel-air ratio, for instance for 20° main throttle opening, then it may take 40° opening for the bypass throttle 175 of FIG. 23 to achieve the same bypass airflow, since the matrix 170 causes some throttling.

However, as far as the transient curves are concerned, there exists an important difference between the devices FIG. 22 & FIG. 23. Referring back to the throttle positions illustrated in FIG. 7, it can be seen that the bypass throttle is passing more air at the lower part of the roadload curve than at its upper part. Consequently, if the device of FIG. 23 replaces the device of FIG. 6, the curve *i* is influenced by a higher percentage of matrix produced suction, with the result that the curve *i* will now be steeper than curve *k*.

In chapter 6d it was said that different shunts can produce a "variation in the slant angle between members of the family of transient curves." The difference in slant angle produced by the device of FIG. 6 and FIG. 23 illustrates this influence.

In the device of FIG. 24 the parallel shunted matrix and venturi of FIG. 22 is combined with the "Airvalve Reset device" explained in Chapter 10d and FIG. 18. All parts of FIG. 24 are identical to those of FIG. 22, except for the airvalve reset throttle 179. What was said in Chapter 10d, about the scheduled connection between the reset throttle 179 and the main throttle, also applies to FIG. 24.

FIG. 24 gives an example that the seven different reset devices, described in Chapter 10, are interchangably usable in combination with the different matrix-venturi shunt systems, described in Chapter 11.

c. Matrix in Airbleed Passage (FIG. 25)

The bleed air inlet 181 delivers bleed air to the laminar flow matrix 180, arranged in the Bleed Air Passage 182. This passage connects to the Bleed Chamber 183, which discharges by means of the discharge port 184 into the venturi 185. The fuel metering orifice 186 receives the fuel from a fuel level holding device (not shown) and discharges into the bleed chamber 183. The metering suction prevailing in the chamber 183 determines the fuel discharge and is produced by the venturi suction, diminished by an amount caused by the bleed airflow. The main throttle 187 controls the bypass throttle 188 by means of a reset scheduling mechanism similar to that shown in FIG. 6.

The metering suction curve plotted against airflow for this device is shown in FIG. 27, curve "C."

FIG. 28, curve "c," shows the fuel air ratio curve, resulting from this metering suction "C."

In order to understand this new carburetor it will first be compared to the conventional carburetors shown in FIG. 26A and FIG. 26B. In FIG. 26 A, the conventional turbulent bleed orifice 190, connects to the bleed chamber 193. The fuel metering orifice is shown at 196. The foam composed of the metered fuel and bleed air is discharged at the port 194 into the venturi 195. The carburetor of FIG. 26B is only equipped with a single solid fuel discharge orifice 199.

The curve "B" in FIG. 27 represents the metering suction acting on the solid fuel discharging orifice 199. This suction curve produces the fuel-air ratio curve "b" of FIG. 28.

The curve "A" of FIG. 27 is the metering-suction curve produced inside the bleed chamber 193 of the conventional carburetor FIG. 26A. For equal flow areas of the fuel orifices 199 and 196, the bleed chamber metering suction generates the mixture curve "a" (FIG. 28), which parallels curve "b" at a lower level. In other words: A simple fixed airbleed orifice produces NO low-end correcting influence on the fuel air ratio curve; it merely lowers this curve and improves atomization.

Returning now to the effect on the metering curve created by the bleed air matrix 180 of FIG. 25, it can be seen that the metering suction curve "C" of FIG. 27 produced by this device rises at the LOW end almost to the curve "B." The reason is again that the flow resistance of the matrix INCREASES RELATIVE to that of a turbulent orifice, for DIMINISHING flow.

The fuel-air ratio curve resulting from this condition is "c" in FIG. 28. It exhibits the desired low airflow enriching effect.

This demonstrates that the matrix shunted into an airbleed produces transient curves which are similar to the curves *i h j* of FIG. 7. Furthermore, just as in the case of the device composed of a matrix and venturi in series (FIG. 6), the carburetor of FIG. 25 can be combined with any of the reset devices explained in Chapter 10.

The advantage of the new carburetor according to FIG. 25 is that a very small matrix can be used, since it handles bleed air only. Furthermore, with only a venturi intersecting the main airflow, better recovery is obtained than with the device of FIG. 6, thus making it possible to extend the range of the bleedair matrix carburetor.

d. Matrix controls Float Bowl Vent (FIG. 29 & 33)

In this carburetor, the matrix produced suction curve modifies the metering pressure drop indirectly, by creating a small suction in the floatbowl. The force controlling the fuel flow through the metering orifice is of course the pressure drop through the orifice. Consequently, a suction at the floatbowl vent in the device shown in FIG. 29 has the same effect as an equal REDUCTION of metering suction in the bleed chamber 183 of FIG. 25.

In FIG. 29, a relatively small bypass airflow is controlled by a matrix 200 and the preceeding air orifice 201. This airflow discharges into the venturi 205, through the port 203. The fuel metering orifice 204 also discharges directly into the venturi 205. The main throttle 207 is coupled to the reset device, in the manner described in chapter 3. In this example the airvalve reset device 208 (Chapter 10d) is chosen.

The metering orifice 204 receives the fuel from the floatbowl 210. The float 211 is hinged at the pivot 212 and operates the fuel inlet needle valve 213. The float controls the float level 214. The air pressure on top of this float level is established through the vent 215. Unlike conventional atmospheric vents, this vent connects to a junction space 202 shunted between the air orifice 201 and the matrix 200.

In order to understand the influence of this Matrix shunting, it is again advantageous to compare the carburetor of FIG. 29 with an equivalent carburetor, where the matrix is replaced by a turbulent orifice. FIG. 30 shows this hypothetical carburetor, which is identical to that of FIG. 29, except for the second air orifice 220 which takes the place of the matrix 200.

FIG. 31 shows the suction curves plotted against airflow, produced by both devices. Curve "A" represents the venturi throat suction prevailing at the exit of the metering orifice 204 and 225 in BOTH carburetors of FIG. 29 and FIG. 30.

The curve "B" is the suction generated in the air-space 222 of FIG. 30. Since this space communicates through the vent 224 to the floatbowl, this suction has to be DEDUCTED from the venturi suction prevailing at the orifice, in order to obtain the actual metering pressure drop. Consequently, the suction values "A-B" produce the fuel discharge.

FIG. 32 shows the resulting fuel-air ratio curves. Curve "a" is the ratio which would have been obtained if the bowl WOULD be vented to atmosphere, so that the full venturi suction "A" of FIG. 31 creates the metering pressure drop.

Curve "b" of FIG. 32 represents the fuel-air ratio derived from the metering pressure drop of the device FIG. 30, with vent connection into the suction chamber 222. It can be seen, that, with the use of two turbulent air orifice 220 and 221, only a lowering of the ratio results, WITHOUT the benefit of any compensation; curve "a" and curve "b" are simply equivalent, on different mixture levels.

The situation becomes different with the use of the laminar flow matrix 200 in FIG. 29. With DECREASING airflow, the flow RESISTANCE of the matrix INCREASES RELATIVE to the flow resistance of the turbulent orifice 201. At low airflows, the matrix simulates an almost closed valve. Consequently, at low airflows, the airflow through the orifice 201 is greatly reduced, and therewith the pressure drop through 201 practically disappears. At low airflows, the suction curve "C" in the space 202 drops off to almost atmospheric pressure. The result is that the fuel-air ratio curve "c" of the device of FIG. 29 increases to richer values, at the low airflow end.

It follows that the matrix, controlling the float bowl pressure can also produce the transient curves *i,j* and *k* of FIG. 7, and that the reset device must function similar to that of FIG. 18. The airvalve reset device 208 is preferable in the carburetor of FIG. 29, since it can also be used to provide the necessary idle enrichment (See Chapter 10d).

It should be understood that the port 203 does NOT have to be located in the venturi throat, as shown in FIG. 29. This port can communicate with a different, larger area of the venturi, according to the demands of the desired correction. A location of port 203 at a point

of smaller suction reduces the slope of the correction curve and also the length of the matrix.

The carburetor shown in FIG. 33A is identical to FIG. 29, except for a variable air orifice 230, which replaces the fixed orifice 201 of FIG. 29. This variable air orifice can replace other reset devices, by being controlled from the main throttle 231. It consists of a plate valve 232, which is also shown in its sideview in FIG. 33 B, a view taken generally on the plane of line B—B of FIG. 33-A and looking in the direction of the arrows. This plate valve is rotated by the main throttle shaft 233. The plate valve carries a profiled slot 234, which registers with the air orifice 230. The shape of this slot determines the flow to the matrix, and therewith "resets" the suction curve which is produced in the floatbowl, by communication through the vent 235.

This reset device also influences the slant angle of the transient curves. If used in combination with a second reset device, as for instance again an airvalve 238, any combination of shapes of the roadload curve and the transient curves becomes possible. Thus, the carburetor FIG. 33 combines the greatest possible freedom and versatility of shaping the two kinds of metering curves with the advantage of a small laminar flow matrix.

12. MATRIX CONTROLS EXCESSIVELY RICH CARBURETOR WITH AIR DILUTION BY MEANS OF INTERIOR DISCHARGE THROTTLE (FIG. 34, 35 & 36)

The basic system shown in the schematic FIG. 34, makes it possible to combine the use of a very small laminar flow matrix with the first explained simple system which uses the series shunt of the matrix and the venturi (FIG. 6 Chapter 3), or the parallel shunt of the matrix and venturi (FIG. 22, Chapter 11b). This is accomplished by scaling these previously described carburetors down, fitting them with a large metering orifice to generate an Excessively Rich mixture, and subsequently diluting this mixture to the correct roadload curve, by means of an oversized Interior Discharge Throttle Reset system, (previously explained in chapter 10b and FIG. 15).

The matrix 240 and the venturi 241 create the metering suction acting on the fuel metering orifice 242, which receives fuel from a fuel level holding mechanism (not shown). The discharge of the Excessively Rich mixture, produced by this small carburetor 244, is controlled by the throttle 243. This mixture is delivered into the carburetor outlet passage 246, which is subjected to the manifold vacuum. The large Interior Discharge Throttle 245 delivers air into the same passage 246. The throttle 245 is controlled by the throttle 243, by means of a scheduling mechanism similar to that shown in FIG. 15. The cam shape, and therewith the opening schedule, must, of course, fit the special requirements of FIG. 34, and dilute the excessively rich mixture to the desired values (as given by the roadload curve), over the entire opening range.

The carburetor shown in FIG. 34 is related to the carburetor with the Interior Discharge Reset system shown in FIG. 15 and explained in chapter 10 b. In FIG. 15, the interior discharge throttle 91 is used for resetting only. In FIG. 34, the interior discharge throt-

tle 245 is scheduled to serve two purposes: First it is opened about proportionally with the throttle 243, in order to dilute the mixture. Secondly, SUPERIMPOSED on this proportional opening movement, is the reset movement.

In other words: The throttle 243 is the equivalent of the main throttle 92 of FIG. 15, and the throttle 245 has the resetting task of the throttle 91, PLUS the added task of diluting the excessively rich mixture produced by carburetor 244.

The mixture curves, delivered by the carburetor 244 are proportional to those of FIG. 7; the only difference is the production of a multiple of the fuel-air ratios compared to that of the carburetor of FIG. 6. The air dilution produced by the throttle 245 brings the curves down to the same shape and fuel-air ratio as given in FIG. 7.

It follows that the Excessively Rich Mixture system creates a simple way to reduce the size and cost of the matrix.

FIG. 35 illustrates a modification of the basic system of FIG. 34. The Excessively Rich Mixture carburetor 254 is basically identical to that of FIG. 34. Its discharge 258 has been moved to a central position of the carburetor outlet 256, for improved distribution. Furthermore, a new, second venturi 257 is arranged BEHIND the interior discharge throttle 255. This second venturi boosts the suction of the venturi 251 at the top range of this carburetor, since the discharge 258 reaches into the throat of this venturi.

The function of this system is identical to that of FIG. 34, except that the second interior discharge venturi 257 increases its range, and that the location of the discharge 258 improves distribution and atomization.

FIG. 36 shows an additional modification of the carburetor of FIG. 35. All previously explained New carburetors, constitute only the Primary range of a Two Stage carburetor. The device of FIG. 36, however, combines both stages and covers the entire range. 266 is the first stage, while 270 serves the second stage.

The excessively rich carburetor 266 is identical in function to 254 of FIG. 35. However, the interior discharge throttle 265 is much larger than the throttle 255 of FIG. 35; consequently, when in FIG. 35 the throttle 255 of that primary carburetor is completely open, at the top of the primary range, the throttle 265 of FIG. 36 will have been only partly opened (by the reset mechanism, connecting the two throttles 263 and 265), to deliver the airflow of for instance 120 C.F.M., if the carburetor is dimensioned to fit the requirements of FIG. 7.

During further opening of throttle 265, from 120 C.F.M. to the maximum power at 240 C.F.M. (FIG. 7), the throttle 263 of the primary carburetor remains in its open position, (just as in the case of the primary main throttle of FIG. 7). From 120 C.F.M. to full power at 240 C.F.M., the secondary throttle 273 of the second stage carburetor 264 is opened, together with the throttle 265, which now opens the rest of the way. The fuel metering orifice 272 of this second stage is also dimensioned to provide an excessively rich mixture, which then will be properly diluted by means of the upper opening portion of the large interior discharge throttle 265.

The second stage is here again shown as a conventional carburetor. However, it is entirely possible to use the new carburetor system also for this second stage.

13. CONCLUSION

5

It is to be understood that the invention is not restricted to the forms of execution shown in the drawings: All of the Reset systems can be combined with all of the Matrix-Venturi Shunt systems. Furthermore, all of these combinations can be fitted either with a Laminar Flow Matrix, or with the Device Simulating a Laminar Flow Matrix.

The new carburetor was explained as a single orifice carburetor, in order to restrict the explanation to the new features. It is to be understood that the combination of the new metering system with conventional idle orifice systems and/or power jet systems is possible.

The preferred embodiment of the invention is shown in FIG. 29, for use as primary stage in Two stage carburetors, and in FIG. 36 for single barrel carburetors.

I claim:

1. A two stage carburetor for an internal combustion engine having a primary carburetor section and a secondary carburetor section, at least said primary carburetor section comprising

- a. a throttle body containing at least one main induction passage,
- b. at least one main throttle arranged in said main induction passage for controlling the flow of combustible mixtures from said induction passage and into said engine,
- c. at least one fuel level holding device,
- d. means for producing a fuel metering vacuum,
- e. at least one fuel metering orifice effective for receiving fuel from said fuel level holding device and being subjected to said fuel metering vacuum,
- f. said means for producing a fuel metering vacuum comprising first vacuum generating means for developing a first vacuum of variable value in the vicinity of said fuel metering orifice dependent upon the rate of air flow through said main induction passage, second vacuum generating means for developing a second vacuum of variable value in the said vicinity of said fuel metering orifice dependent upon the rate of air flow through said main induction passage, the value of said first vacuum of variable value varying at a rate different from the rate at which said second vacuum of variable value varies with respect to said rate of air flow through said main induction passage, said first and second vacuums effectively combining in said vicinity to result in a pneumatic summation thereof to define said fuel metering vacuum also of a variable value, said fuel metering vacuum having a relationship to the rate of air flow through said main induction passage expressed by the equation $\Delta P \propto C.F.M.^x$ wherein:

1. ΔP represents the pressure differential created by said fuel metering vacuum

2. C.F.M. represents the cubic feet of air flow per minute and

3. the exponent X has a value greater than 1.2 but less than 1.9, thereby creating a fuel-air ratio curve of said combustible mixture which becomes richer in fuel with reduced airflow,

g. at least one reset device comprising means to vary the said fuel-air ratio and comprising a scheduling mechanism which couples said means to vary the fuel-air ratio to said main throttle, said mechanism scheduling the magnitude of fuel-air ratio variations in dependence of opening positions of the main throttle, said scheduling mechanism being calibrated to correct said fuel-air ratio, which becomes richer with reduced airflow, to the desired roadload curve,

h. the secondary carburetor comprising a secondary main throttle, and a scheduling mechanism which couples said means to vary the fuel-air ratio of the primary carburetor to said secondary main throttle, said mechanism scheduling the magnitude of fuel-air ratio variations of said primary carburetor in dependence of opening positions of said secondary main throttle, said scheduling mechanism being calibrated to correct the fuel-air ratio of said primary carburetor to compensate for fuel-air ratio aberrations of the secondary carburetor.

2. A carburetor for an internal combustion engine, comprising

- a. at least one throttle body containing at least one first passage means for the formation and conduction of an excessively rich fuel-air mixture,
- b. at least one throttle means arranged in said first passage means for controlling the flow of said mixture therewith,
- c. at least one fuel level holding device,
- d. first means situated in said first passage means for producing a fuel-metering pressure differential,
- e. at least one fuel metering orifice effective for receiving fuel from said fuel level holding device and being subjected to said fuel-metering pressure differential for producing said excessively rich fuel-air mixture,
- f. an additional large throttle body containing a main passage,
- g. an air throttle arranged in said main passage,
- h. a venturi arranged in said main passage downstream of said air throttle,
- i. said first passage means being arranged for discharging said excessively rich fuel-air mixture into said venturi arranged in said main passage,
- j. said first means situated in said first passage means comprising first vacuum generating means for developing a first vacuum of variable value in the vicinity of said fuel metering orifice dependent upon the rate of air flow through said first passage means, second vacuum generating means for developing a second vacuum of variable value in the said vicinity of said fuel metering orifice dependent upon the rate of air flow through said first passage means, the value of said first vacuum of variable value varying at a rate different from the rate at which said second vacuum of variable value varies with respect to said rate of air flow through said first passage means, said first and second vacuums effectively combining in said vicinity to result in a pneumatic summation thereof to define said fuel-metering pressure differential also of a variable value, said fuel-metering pressure differential having a relationship to the rate of air flow through said first passage means expressed by the equation $\Delta P \propto C.F.M.^x$ wherein:

1. ΔP represents the value of said fuel-metering pressure differential,
2. C.F.M. represents the cubic feet of air flow per minute and
3. The exponent X has a value greater than 1.2 but less than 1.9, thereby creating a fuel-air ratio curve for said mixture which becomes richer in fuel with reduced airflow,
4. and a scheduling mechanism operatively coupling said air throttle to said mixture-controlling throttle means so as to cause said air throttle to function as a reset device whereby changes in the fuel-air ratio of said mixture are affected by opening of said air throttle, said mechanism scheduling the magnitude of said fuel-air ratio changes caused by said air throttle in dependence of opening positions of the said mixture-controlling throttle means, said scheduling mechanism being calibrated to correct said excessively rich fuel-air ratio, which becomes richer with reduced airflow, to the desired roadload curve.
5. The carburetor of claim 2 with two excessively rich carburetors working progressively in the manner of two stage carburetors.
6. A carburetor for an internal combustion engine, comprising a throttle body, a main induction passage formed therethrough, at least one throttle valve situated in said induction passage for movement relative thereto in order to thereby variably control the flow of a fuel-air mixture through said induction passage, a venturi in said induction passage upstream of said throttle valve, first air bleed means including a bleed air chamber, first conduit means communicating between said air bleed chamber and said induction passage at said venturi, fuel supply conduit means including fuel metering orifice means communicating between a related source of fuel and said bleed air chamber, air passage means communicating between a related source of substantially ambient atmospheric air and said bleed air chamber, means situated in said air passage means defining a laminar flow matrix means, said laminar flow matrix means being effective to produce a vacuum in said bleed air chamber in response to air flow through said venturi in order to thereby determine the rate of flow of said fuel from said fuel supply conduit means into said bleed air chamber and through said first conduit means into said induction passage, said laminar flow matrix means being effective to provide a restrictive effect to the flow of said air through said air passage means sufficient to cause the fuel-air ratio curves for variable engine R.P.M. at constant throttle positions to be displaced towards richer fuel-air ratio values at the low R.P.M. end of said curves if compared to fuel-air ratio curves recorded with the same carburetor but without said laminar flow matrix means being installed in said air passage means, and at least one reset means effective for varying the fuel-air ratio of the fuel and air flowing through said induction passage, said reset means comprising scheduling means operatively coupling said reset means to said throttle valve in order to thereby cause said reset means to be actuated in response to opening and closing movement of said throttle valve, said scheduling means being effective for variably and in accordance with the position of said throttle valve reducing the effect of said laminar flow matrix means in determining

- the value of the fuel-air ratio curves at constant engine R.P.M.
5. The carburetor of claim 4 in which said reset means comprises a bypass air throttle and said scheduling means comprises a lever and cam device operatively connecting said throttle valve with said bypass air throttle.
  6. The carburetor of claim 4 in which said reset means comprises an airvalve and said scheduling means comprises a lever and cam device operatively connecting said throttle valve with said airvalve for actuation of said airvalve in response to movement of said throttle valve.
  15. The carburetor of claim 4 in which said reset means comprises an interior discharge throttle, and said scheduling means comprises a lever and cam device operatively connecting said throttle valve with said interior discharge throttle for actuation of said interior discharge throttle in response to movement of said throttle valve.
  20. The carburetor of claim 4 in which said reset means comprises a port in said air passage means connecting ambient air to said bleed air chamber, and a plate valve generally controlling the effective area of said port, said plate valve being operatively coupled to said throttle valve, and said scheduling means comprising contoured slot means formed through said plate valve as to be in general registry with said air passage means.
  25. A carburetor for an internal combustion engine, comprising a throttle body, a main induction passage formed therethrough, at least one throttle valve situated in said induction passage for movement relative thereto in order to thereby variably control the flow of a fuel-air mixture through said induction passage, a venturi in said induction passage upstream of said throttle valve, a fuel reservoir including vent means, fuel delivery passage means including fuel metering restriction means communicating between said fuel reservoir and said venturi, air passage means communicating between a first conduit portion leading to said induction passage and inlet orifice means leading to ambient atmosphere, means situated in said air passage means defining a laminar flow matrix means, a second conduit portion communicating between said vent means and said air passage means at a point downstream of said inlet orifice means but upstream of said laminar flow matrix means, said inlet orifice means and said laminar flow matrix means being effective to alter the magnitude of vacuum in said induction passage in the vicinity of said first conduit portion in order to thereby cause the fuel-air ratio curves for variable engine R.P.M. at constant throttle valve positions to be displaced towards richer fuel-air ratio values at the low R.P.M. end of said curves if compared to fuel-air ratio curves recorded with the same carburetor but without said laminar flow matrix means being installed in said air passage means, and at least one reset means effective for varying the fuel-air ratio of the fuel and air flowing through said induction passage, said reset means comprising scheduling means operatively coupling said reset means to said throttle valve in order to thereby cause said reset means to be actuated in response to opening and closing movement of said throttle valve, said scheduling means being effective for

variably and in accordance with the position of said throttle valve reducing the effect of said laminar flow matrix means in determining the value of the fuel-air ratio curves at constant engine R.P.M.

10. The carburetor of claim 9 in which said reset means comprises a bypass air throttle and said scheduling means comprises a lever and cam device operatively connecting said throttle valve with said bypass air throttle.

11. The carburetor of claim 9 in which said reset means comprises an airvalve and said scheduling means comprises a lever and cam device operatively connecting said throttle valve with said airvalve.

12. The carburetor of claim 9 in which said reset means comprises an interior discharge throttle and said scheduling means comprises a lever and cam device operatively connecting said throttle valve with said interior discharge throttle.

13. The carburetor of claim 9 in which said reset means comprises a plate valve controlling said inlet orifice means, said plate valve being operatively coupled to said throttle valve, and said scheduling means comprising contoured slot means formed generally through said plate valve and in general registry with said inlet orifice means.

14. A carburetor for an internal combustion engine, comprising a carburetor body, induction passage means formed through said body for communicating between a source of air and an intake of said engine, variably positionable and openable throttle valve means situated within said induction passage means for controlling the flow of air and fuel through said induction passage means and into said intake of said engine, a source of fuel, fuel discharge means communicating with said source of fuel and situated as to discharge metered fuel flow into said induction passage means at a point upstream of said throttle valve means, first vacuum generating means for developing a first vacuum of variable value in the vicinity of said fuel discharge means dependent upon the rate of air flow through said induction passage means, second vacuum generating means for developing a second vacuum of variable value in the said vicinity of said fuel discharge means dependent upon the rate of air flow through said induction passage means, the value of said first vacuum of variable value varying at a rate different from the rate at which said second vacuum of variable value varies with respect to said rate of air flow through said induction passage means, said first and second vacuums effectively combining in said vicinity to result in a pneumatic summation thereof to define a metering vacuum of variable value in said vicinity causing the rate of flow of said metered fuel flow to be dependent upon the value of said metering vacuum, and additional means responsive to demands for increased power from said engine for at least temporarily increasing the value of said metering vacuum.

15. A carburetor according to claim 14, wherein said additional means is operatively connected to said throt-

tle valve means.

16. A carburetor according to claim 14, wherein said first vacuum generating means comprises a venturi formed in said induction passage means.

17. A carburetor according to claim 14, wherein said first vacuum generating means comprises a venturi formed in said induction passage means, and wherein said second vacuum generating means comprises airflow restriction means having a characteristic of producing a flow of air therethrough generally proportional to the pressure differential across said restriction means.

18. A carburetor according to claim 14, wherein said fuel discharge means comprises first fuel discharge port means opening at one end into said induction passage means, a chamber formed upstream of said discharge port and in communication with the other end of said fuel discharge port, fuel delivery conduit means communicating between said source of fuel and said chamber, air passage means communicating between a source of air and said chamber, and wherein said second vacuum generating means is situated within said air passage means.

19. A carburetor according to claim 14, wherein said additional means comprises variably openable air bleed means effective for admitting bleed air into said induction passage means, said air bleed means being moved toward a more nearly closed position in response to said demands for increased power from said engine.

20. A carburetor according to claim 19, wherein said bleed air is admitted into said induction passage means generally at a point upstream of said throttle valve means.

21. A carburetor according to claim 14, wherein said second vacuum generating means comprises air-flow restriction means having a characteristic of producing a flow of air therethrough generally proportional to the pressure differential across said restriction means.

22. A carburetor according to claim 21, wherein said restriction means comprises a matrix of laminar flow conduit portions.

23. A carburetor according to claim 14, wherein said additional means comprises a bleed air passage communicating generally between a source of air and said induction passage means. A variably positionable air valve for controlling the rate of flow of air through said bleed air passage, and linkage means operatively interconnecting said throttle valve means and said air valve.

24. A carburetor according to claim 23, wherein said bleed air passage communicates generally between a source of air and said induction passage means at a point generally above said throttle valve means.

25. A carburetor according to claim 23, wherein said linkage means comprises cam means contoured as to generally cause said air valve to further restrict the flow of said bleed air through said bleed air passage means as said throttle valve means is moved from an idle position to a more nearly wide open position.
